MUSIC STAND STORAGE CART

Robert B. Mero, 15 Castle Drive, Potsdam, N.Y. 13676

Filed Feb. 6, 1967, Ser. No. 5,707

Term of patent 14 years

(Cl. D33—14)

FIG. 1

FIG. 3

FIG. 1 is a perspective view of a music stand storage cart showing my new design;

FIG. 2 is a top plan;

FIG. 3 is an end view of the invention taken from the open end thereof, along the lines 3—3 of FIG. 2.

I claim:

The ornamental design for a music stand storage cart, as shown.
